UNITED STATES PATENT OFFICE

158,871

FISH LURE

Jacob I. Koski, Ashtabula, Ohio

Application April 23, 1948, Serial No. 145,930

Term of patent 3½ years

(Cl. D31—4)

To all whom it may concern:

Be it known that I, Jacob I. Koski, a citizen of the United States, residing at Ashtabula, in the county of Ashtabula and State of Ohio, have invented a new, original, and ornamental Design for a Fish Lure, of which the following is a specification, reference being had to the accompanying drawing, forming part thereof.

Figure 1 is a top perspective view of a fish lure, showing my new design, and

Figure 2 is an underside perspective view thereof.

I claim:

The ornamental design for a fish lure, as shown.

JACOB I. KOSKI.
